C. W. KETTLER.
JAR AND OTHER RECEPTACLE.
APPLICATION FILED DEC. 31, 1918.

1,307,363.

Patented June 24, 1919.

UNITED STATES PATENT OFFICE.

CARL WILLIAM KETTLER, OF WARWOOD, WEST VIRGINIA, ASSIGNOR OF ONE-HALF TO
ALFRED INGRAM AND HARRY INGRAM, BOTH OF BROOKLYN, NEW YORK.

JAR AND OTHER RECEPTACLE.

1,307,363.

Specification of Letters Patent. Patented June 24, 1919.

Application filed December 31, 1918. Serial No. 269,140.

To all whom it may concern:

Be it known that I, CARL WILLIAM KETTLER, a citizen of the United States, and a resident of Warwood, in the county of Ohio 5 and State of West Virginia, have invented certain new and useful Improvements in Jars and other Receptacles, of which the following is a specification.

The invention pertains more particularly to jars and other receptacles made of glass, earthenware or like material of a fragile nature, and it resides in a novel construction adapting the jar to receive a cover and suitable means whereby the cover may be secured on the jar. Glass and earthenware jars have been variously constructed to receive bails and cover-locking means, but the fragile nature of the material of the jar has rendered it difficult to provide thereon suitable means for adequately receiving the bails and cover-locking features. In accordance with my invention I form the jar in opposite sides of its upper or neck portion with integral lugs of special construction and apply thereto metallic ears affording bearings for the lever element or bail of the cover locking features, and at the same time dispense with one of the wires commonly found on jars to coöperate with the locking wire bails. 30 My invention presents several features of novel construction and advantage, and the same will be understood from the detailed description hereinafter presented, reference being had to the accompanying drawings, in 35 which:

Figure 1 is a side elevation of the upper portion of a glass jar equipped with the features of my invention;

Fig. 2 is a vertical section through the same, taken on the dotted line 2—2 of Fig. 1;

Fig. 3 is a horizontal section through a portion of the same, taken on the dotted line 3—3 of Fig. 1, and

Fig. 4 is a side elevation of a portion of the jar minus the cover, metallic ear and cover-locking features.

In the drawings, 10 designates a jar, 11 the contents thereof, 12 an applied cover, 13 50 a gasket to receive the downwardly extended edge portions of said cover, 14 a wire locking-bail engaging said cover for securing the same in position, and 15 a semi-circular lever-bail or wire for binding the bail 14 in firm position across the top of the cover 12.

The jar 10 has around its upper portion a reduced circumferential flange 16 and exterior thereto a circumferential or annular horizontal shoulder 17 affording a seat for the gasket 13. The jar 10 is also formed below said shoulder 17 with an annular groove 18, which need not necessarily extend entirely around the neck of the jar, since I only utilize portions of said groove for the purposes of my invention. The jar 10, except for the features entering into my invention, may be of any usual or suitable form and construction.

On opposite sides of the neck 19 of the jar and formed integrally therewith are vertical lugs 20 which extend downwardly from and are integral with an annular portion or shoulder 21 located directly below and forming the lower wall of the annular groove 18, and said lugs 20 are preferably of key-stone 75 outline and have a plain horizontal lower end 22 and upwardly diverging undercut sides 23, the upper end of the lugs 20 being flush with and not distinguishable from the lower surface of the annular shoulder 21. 80 The lugs 20 have plain vertical outer faces, as shown, although this feature is not entirely essential to my invention.

Upon the lugs 20 I apply ears, as they may be termed, 24, of special construction, these 85 ears being of sheet metal and having a lower flange 25 to engage the lower end of the lugs 20, inwardly bent side flanges 26 to closely engage the undercut side surfaces 23 of the lugs 20, upwardly extending tongues 27 bent 90 inwardly to enter the annular groove 18 of the jar and outwardly convexed circular face portions 28 which are spaced from the lugs 20 and have openings 29 to receive the inwardly bent ends 30 of the locking wire bail 95 15, the edges of said openings 29 affording bearings for said ends 30. The ears 24 conform generally to the outline of the lugs 20, but at their tongue portions 27 extend above said lugs so as to enter into locking engagement with the annular groove 18.

The locking bail 14 is of wire, as usual, and at its upper middle portion is adapted to a recess 31 in the cover 12, and the sides of said bail 14 extend downwardly at opposite 105 sides of the jar and said sides at their lower ends are bent inwardly, as at 32, and confined in eyes 33 formed in the end portions of the locking wire or bail 15. The locking wire or bail 15 is substantially semi-cir- 110

cular and extends around about one-half of the neck of the jar and at its end portions is formed with the eyes 33 and upwardly extending members 34, whose upper ends 5 are bent inwardly, as at 30, to enter the openings 29 in the ears 24, as will be clearly understood from the drawing without minute explanation. When the locking elements 14, 15 are in their operative position, shown 10 in Fig. 1, the lower ends of the bail 14 are carried beyond the center line of the ends 30 of the bail 15 and said bail 14 then serves to lock the cover 12 in position. When it is desired to remove the cover 12, the middle 15 portion of the bail 15 is turned to carry the lower side portions of the bail 14 to the opposite side of the center of the ends 30 of said bail 15, thereby releasing the strain on the bail 14 and permitting said bail to 20 be turned from over the cover 12.

The lugs 20 by being integral with the jar 10 and having no part to be chipped off in the manipulation of the wire operating elements of the cover, constitute one essential 25 feature of my invention, and these lugs plus the metallic ears 24 of the character described afford adequate means for receiving and for the manipulation of the locking bails 14, 15 whose strains, during manipulation, are partly borne by the ears 24 and partly by the lugs 20. The lugs 20 prevent any upward movement of the ears 24 during the manipulation of the locking features 14, 15 and the coöperative action of the 30 tongues 27 and shoulder afforded by the groove 18 prevents any downward slipping of the ears 24 from the lugs 20, the spring action of the tongues 27 being supplemented by the close frictional engagement of the 35 sides of the ears 24 with the sides of the lugs 20.

My invention permits me to produce a very durable glass jar of the character requiring the locking elements 14, 15, and to 40 avoid a third wire which is commonly employed in jars of this class connecting the ends of the lever member 15 of the locking features. The purpose of the present invention is to provide an adequate construction 45 of glass or earthen jar or receptacle adapted to adequately receive and care for the locking wires whereby the cover may be secured on the jar. It will be readily seen that in accordance with the construction 50 presented by me, there is no strain on the lugs 20, except that applied against their lower broad ends and that the upper ends of said lugs do not project outwardly beyond adjacent surfaces of the jar and that therefore 55 there is little or no danger of said lugs ever becoming injured by the action of the locking wires.

I do not limit my invention to all of the special details of form and construction shown, because I am aware that some of 60 these details may be modified without departure from the spirit of my invention. For illustration, the groove 18 is shown as extending entirely around the neck of the jar and in that respect adds to the ornamental character of the jar, but from a mechanical point of view the groove 18 affords recesses above the lugs 20 to receive the tongues 27 of the ears 24, and therefore it is not essential that the groove 18 be extended beyond the vertical planes of the lugs 20.

What I claim as my invention and desire to secure by Letters-Patent, is:

1. A jar or other receptacle, a cover therefor, a substantially semi-circular locking-bail for said cover and a substantially semi-circular side lever-bail receiving the lower ends of said locking bail, said jar having integrally therewith vertical lugs at opposite sides of the neck thereof, combined with metallic ears applied upon and engaging the sides and lower ends of said lugs and having bearings to receive the inwardly bent ends of the said lever bail. 80

2. A jar or other receptacle, a cover therefor, a substantially semi-circular locking bail for said cover and a substantially semi-circular side lever bail receiving the lower ends of said locking bail, said jar having integrally therewith vertical lugs at opposite sides of the neck thereof and recesses above said lugs, combined with metallic ears applied upon and engaging the sides and lower ends of said lugs and having bearings to receive the inwardly bent ends of said lever bail and also upwardly extending inwardly bent tongues within said recesses. 95

3. A jar or other receptacle, a cover therefor, a substantially semi-circular locking bail for said cover and a substantially semi-circular side lever bail receiving the lower ends of said locking bail, said jar having integrally therewith vertical lugs at opposite sides of the neck thereof and which lugs 105 have plain lower ends and inwardly beveled sides, combined with metallic ears applied upon and engaging said lower ends and sides of said lugs and having outwardly convexed bearings to receive the inwardly bent ends 110 of said lever bail. 115

Signed at Wheeling in the county of Ohio and State of West Virginia this 10th day of December A. D. 1918.

CARL WILLIAM KETTLER.
